UNITED STATES PATENT OFFICE.

EDWIN G. LITTLE, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-SWITCH-OPERATING APPARATUS.

Application filed June 29, 1927. Serial No. 202,273.

My invention relates to railway switch operating apparatus, and has for an object the provision of means for permitting manual operation of a power-operated switch.

5 I will describe one form of apparatus embodying my invention, and will then point out the novel features thereof in claims.

In the accompanying drawings, Fig. 1 is a plan view showing a railway switch provided with one form of operating apparatus embodying my invention. Fig. 2 is a plan view showing the selecting mechanism B forming part of the switch operating apparatus shown in Fig. 1. Fig. 3 is a longitudinal sectional view of the mechanism shown in Fig. 2, and Fig. 4 is a transverse sectional view of the mechanism shown in Fig. 2. Fig. 5 is a fragmentary view showing a circuit controller C forming part of the mechanism 10 shown in Fig. 2 and a portion of the means for operating such circuit controller. Fig. 6 is a detail view showing means for interlocking the bars 3, 4 and 5 in Fig. 2.

Similar reference characters refer to similar parts in each of the several views.

Referring first to Fig. 1, the reference character A designates a railway switch comprising switch rails 15 and 15^a, which rails are connected, as usual, by a front rod 30 16 and a lock rod 17.

The reference character P designates a power switch-actuating mechanism comprising, in the form here shown, an electric motor 18, a switch-operating device 19, and a 35 switch-locking device 20. The operating device 19 actuates a bar 5, and the locking device 20 controls a bar 7, both of which bars extend beneath the rails of the switch and enter a selecting device B which is located on the other side of the switch from the power mechanism P.

Operatively connected with the front rod 16 of the switch A is a bar 4 which projects into the selecting mechanism B, and operatively connected with the lock rod 17 is a bar 6 which, likewise, projects into the selecting mechanism B.

Referring now to Figs. 2, 3 and 4, the selecting mechanism B, in the form here shown, comprises a suitable casing provided with guides to receive the bars 4, 5, 6 and 7 as well as a bar 3. This bar 3 is operatively

connected with a manually operable switch-actuating mechanism, comprising a hand lever 1 fixed to a shaft 2, which is suitably journaled in the wall of the mechanism casing. Also fixed to the shaft 2 on the inside of the casing, is a miter gear 23, meshing with a second miter gear 24 which is mounted to rotate on a stud 28 mounted in the floor of the mechanism case. The second gear 24 carries an arm 25 which is pivotally connected by a link 26 with a lug 27 fixed to the upper surface of the bar 3. It will be seen, therefore, that oscillation of the hand lever 1 will result in longitudinal motion of the bar 3.

Located within the case of the mechanism B is a shifter plate 11 mounted in suitable guides to slide longitudinally in a direction 70 perpendicular to the bars 3, 4, 5, 6 and 7. The shifter plate is provided at one end with a slot to receive two blocks 9 and 10, whereby these blocks are free to slide in the shifter plate in a direction perpendicular to the direction of motion of the shifter plate, so that these blocks slide in the direction of motion of the bars 3, 4 and 5. The blocks 9 and 10 co-act with recesses cut in the under sides of the bars 3, 4 and 5, the manner in which this 80 coaction occurs being explained hereinafter. The other end of the shifter plate 11 carries a third block 8, which may also slide on the shifter plate in a direction perpendicular to the direction of motion of the plate. 85 Block 8 is held in place by a tongue on its under surface, which tongue slides in a slot 21 cut in the shifter plate. The block 8 co-acts with slots cut in the under surfaces of the bars 6 and 7, the manner in which this 90 coaction occurs being explained hereinafter.

The shifter plate 11 is actuated by a hand-operable lever 13 fixed to a shaft 31, which projects through the wall of the casing and carries a cam 12 co-acting with a slot formed 95 by lugs 33 projecting upwardly from the shifter plate. The shaft 31 also carries a cam 14, which co-acts with a yoke 22 pivotally mounted at 32 in the mechanism case. This yoke 22 is connected with a link 29, which in turn is connected with the operating arm 30 of a circuit controller C (see Fig. 5). This circuit controller C controls the supply of power to the power switch-actuating mecha-

nism P, the control being such that when the arm 30 is swung downwardly to the position shown in Fig. 5, the supply of power to the mechanism P is discontinued, whereas when this arm is swung upwardly power may be supplied to the mechanism P under the control of suitable apparatus which forms no part of my present invention, and is consequently omitted from the drawing.

10 As shown in Figs. 2, 3 and 4, the selecting mechanism is in such position that the switch A of Fig. 1 may be operated by hand. That is to say, lever 13 is swung to its left-hand position, so that cam 12 has moved 15 the shifter plate 11 to its extreme right-hand position as viewed in Figs. 2 and 3, with the result that block 9 co-acts with bars 3 and 4 to connect these bars for simultaneous movement. Block 10 co-acts with bar 5, but serves 20 no purpose other than to act as a guide for the right-hand side of block 9 as viewed in Fig. 3. Block 8 co-acts with bar 7 but not with bar 6, with the result that the lock rod 17 of switch A is disconnected from bar 7 and 25 so is disconnected from the locking device 20 of the power actuating mechanism P. The switch A may now be actuated by swinging the hand lever 1, thereby rotating gears 23 and 24 and so sliding bar 3 upwardly, as 30 viewed in Fig. 2. Bars 3 and 4 being operatively connected by the block 9, it follows that this movement of the hand lever 1 will result in moving the switch A to the opposite position from that in which it is shown in 35 Fig. 1. This operation of the switch is not impeded by the locking device 20, because locking bar 7 is disconnected from the lock rod 17 due to the position of block 8.

40 To connect the power mechanism with the switch, the hand lever 13 is swung to its reverse position, thereby causing the cam 12 to slide the shifter plate 11 to the left, as viewed in Fig. 3. Block 10 will then operatively connect bars 4 and 5, and block 8 will operatively 45 connect bars 6 and 7. This operation of the hand lever 13 will also result in shifting the circuit controller C to such position that power may be supplied to the mechanism P. When the mechanism P is operated, bar 5 will 50 be shifted outwardly, and since this bar is coupled with bar 4, the switch A will be moved to its reverse position. Bars 6 and 7 now being coupled together, the switch will be locked in its reverse position by the locking 55 device 20.

When the selector B is to be shifted from the power operating position to the hand operating position, the switch may not occupy the position corresponding to the position 60 of the hand lever 1, so that block 9 cannot enter the recess in bar 3. A similar condition may exist when the selector is to be shifted from the hand operating position to the power operating position. The cam 12

is so designed that in either event the lever 13 may be thrown beyond its vertical position, so that as soon as either the hand lever 1 or the power mechanism P is operated to bring the recesses in the bars into registry with the blocks 8, 9 and 10, the weight of lever 13 will automatically complete the movement of this lever and of shifter plate 11. This results in a saving of time when the selector mechanism B is shifted.

65 Preferably the cams 12 and 14 are so related that when the selector mechanism B is shifted from the power operating position to the hand operating position, circuit controller C is actuated to open the motor circuit before the shifter plate 11 begins to move, and that when the selector mechanism is shifted in the other direction the circuit controller does not close the motor circuit until after the shifter plate has reached its full power operating position. This is a safety 70 feature.

75 Although I have herein shown and described only one form of apparatus embodying my invention, it is understood that various changes and modifications may be made 80 therein within the scope of the appended claims without departing from the spirit and 85 scope of my invention.

90 Having thus described my invention, what I claim is:

95 1. In combination, a railway switch, a power switch actuating mechanism, a manually operable switch actuating mechanism, a bar operatively connected with said switch, a second bar operatively connected with said power mechanism, a third bar operatively 100 connected with said manually operable mechanism, a block mounted to slide transversely with respect to said bars and capable of operatively connecting said first and second bars, a second block mounted to slide transversely with respect to said bars and capable of operatively connecting said first and third bars, and manually operable means for 105 sliding said blocks.

110 2. In combination, a railway switch, a power switch actuating mechanism, a manually operable switch actuating mechanism, a bar operatively connected with said switch, a second bar operatively connected with said power mechanism, a third bar operatively 115 connected with said manually operable mechanism, a pair of blocks capable of occupying two positions in one of which one block operatively connects the first and second bars and in the other of which positions the other block operatively connects the first and third bars, and manually operable means for moving said blocks to one of said positions or the other.

120 3. In combination, a railway switch, a power switch actuating mechanism, a manually operable switch actuating mechanism, a bar operatively connected with said switch, a

- second bar operatively connected with said power mechanism, a third bar operatively connected with said manually operable mechanism, a pair of blocks capable of occupying two positions in one of which one block operatively connects the first and second bars and in the other of which positions the other block operatively connects the first and third bars, a shifter plate carrying said blocks, a cam for sliding said shifter plate to move said blocks into one of said positions or the other, and a manually operable handle for actuating said cam.
4. In combination, a railway switch, a power switch actuating and locking mechanism, a manually operable switch actuating mechanism, a bar operatively connected with said switch, a second bar operatively connected with said power mechanism, a third bar operatively connected with said manually operable mechanism, a fourth bar controlled by the locking portion of said power mechanism, a fifth bar operatively connected with said switch, and manually operable means having two positions in one of which it connects said first and second bars as well as said fourth and fifth bars, and in the other of which it connects the first and third bars but not the fourth and fifth bars.
5. In combination, a railway switch, a power switch actuating mechanism having an actuating device and a locking device, a manually operable switch actuating mechanism and other manually operable means having two positions in one of which it connects the switch with both the operating device and the locking device of said power mechanism, and in the other of which positions it connects the switch with said manually operable actuating mechanism but disconnects the switch from both the operating and the locking devices of said power mechanism.
6. In combination, a railway switch, a power switch actuating and locking mechanism, a manually operable switch actuating mechanism, a circuit controller for governing the supply of power to said power mechanism, and manually operable means having two positions in one of which it connects said switch with said power actuating and locking mechanism and closes said circuit controller, and in the other of which positions it connects the switch with said manually operable actuating mechanism and opens said circuit controller.
7. In combination, a railway switch, a power switch actuating mechanism and a manually operable switch actuating mechanism, three parallel longitudinally slidable bars the first of which is operatively connected with said switch, the second of which is operatively connected with said power mechanism, and the third of which is operatively connected with said manually operable mechanism, said bars having registering notches, a shifter plate slidable transversely with respect to said bars, and having two operative positions, a pair of blocks slidably mounted in said shifter plate and co-acting with the notches in said bars in such manner that when the plate occupies one operative position one block operatively connects the first and the second bars, and that when the shifter plate occupies its other position the other block operatively connects the first and the third bars, and manually operable means for sliding said shifter plate to one or the other of its operative positions.
8. In combination, a railway switch, two separate and distinct means for actuating said switch, a bar operatively connected with said switch, a second bar operatively connected with one of said means, a third bar operatively connected with the other of said means, a sliding block capable of operatively connecting said first and second bars, a second sliding block capable of operatively connecting said first and third bars, and manually operable means for actuating said blocks.
9. In combination, a railway switch, two separate and distinct means for actuating said switch, a bar operatively connected with said switch, a second bar operatively connected with one of said means, a third bar operatively connected with the other of said means, a pair of blocks capable of occupying two positions in one of which one block operatively connects the first and second bars and in the other of which positions the other block operatively connects the first and third bars, and manually operable means for moving said blocks to one of said positions or the other.
10. In combination, a railway switch, two separate and distinct means for actuating said switch, a bar operatively connected with said switch, a second bar operatively connected with one of said means, a third bar operatively connected with the other of said means, a pair of blocks capable of occupying two positions in one of which one block operatively connects the first and second bars and in the other of which positions the other block operatively connects the first and third bars, a shifter plate carrying said blocks, a cam for sliding said shifter plate to move said blocks into one of said positions or the other, and manually operable means for actuating said cam.
11. In combination, a railway switch, two separate devices for actuating said switch, three parallel longitudinally slidable bars the first of which is operatively connected with said switch, the second of which is operatively connected with one of said devices and the third of which is operatively connected with the other of said devices, said bars having registering notches, a shifter plate slidable transversely with respect to said bars, and

having two operative positions, a pair of blocks slidably mounted in said shifter plate and co-acting with the notches in said bars in such manner that when the plate occupies 5 one operative position one block operatively connects the first and the second bars, and that when the shifter plate occupies its other

position the other block operatively connects the first and the third bars, and manually operable means for sliding said shifter plate to one or the other of its operative positions. 10

In testimony whereof I affix my signature.

EDWIN G. LITTLE.
